UNITED STATES PATENT OFFICE.

CHARLES F. PYM, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

GRIPPER MECHANISM.

1,344,316.

Specification of Letters Patent. Patented June 22, 1920.

Original application filed June 24, 1911, Serial No. 635,183. Divided and this application filed November 6, 1917. Serial No. 200,607.

To all whom it may concern:

Be it known that I, CHARLES F. PYM, a subject of the King of Great Britain, residing at Lynn, in the county of Essex and 5 State of Massachusetts, have invented certain Improvements in Gripper Mechanisms, of which the following description, in connection with the accompanying drawings, is a specification, like reference characters on 10 the drawings indicating like parts in the several figures.

This invention relates to gripper mechanisms for use in the manufacture of boots and shoes and is shown as embodied in a 15 mechanism for engaging the upstanding edges of the shoe upper materials to assist in conforming the upper materials to the last. This application is a division of my 20 application, Serial No. 635,183, filed June 24, 1911, and accordingly the present invention is illustrated and described as embodied in a toe lasting mechanism corresponding to that of the application referred 25 to but is not intended to be limited to use in connection with machines of that character.

In the lasting of shoes, the upper materials are conformed to the contour of the last and are folded over the edge of the 30 bottom of a sole mounted on the bottom of the last and tacked or otherwise secured to said sole. Gripper mechanisms may be advantageously employed in the lasting operation to grip the upstanding edges of the 35 upper materials which extend around the edge of the sole and to stretch and tension said materials and conform them closely to the last.

The upstanding edges of the different layers of the upper materials are found in actual practice to be more or less spread apart so that grippers, to be most effective, should provide a relatively wide opening between 40 their opened gripping jaws to receive these upstanding edges and should be so constructed as to gather in all of the upper materials when their jaws are closed. Advantageously a closing movement as short as practicable should be required for one or 45 both jaws.

One feature of my invention consists in a novel construction of gripper mechanism providing gripping jaws arranged in open

position to afford a relatively wide opening to receive the upper materials, the jaws 55 being arranged to have a short relative closing movement—as shown a combined downwardly sliding and inwardly swinging movement of a movable jaw relatively to a fixed jaw—effective to gather in all of the upper 60 materials between the jaws.

When grippers are employed in the lasting of shoes to pull and stretch the upper into close conformity to the last, the best results will be secured by gripping the upper 65 close to the plane of the sole. With this end in view, a further feature of the invention consists in a novel construction and arrangement of gripper jaws in which one jaw is movable relatively to the other from 70 a starting position comparatively remote from the plane of the sole and is mounted and controlled in a novel manner to cause it to receive a component of movement toward the plane of the sole as it swings laterally toward the other jaw and until it arrives substantially at the end of its closing movement. In the construction shown the 75 jaw which receives this movement is the inner jaw, and the other jaw is arranged to 80 engage the upper materials at the outer side and closely adjacent to or in the plane of the sole. Such a construction enables the gripper jaws to engage the upper close to the plane of the sole without striking the sole 85 bottom or the edge of the last in their relative closing movement, and permits the use of grippers having the advantages above set forth in lasting welt shoes since the closing movement of the inner jaw is such that it 90 may clear the upstanding lip or sewing rib of a sole.

When grippers are used in connection with lasting machines, one jaw of the gripper is usually positioned at the outer edge of the 95 shoe bottom to align the opening between the gripper jaws with the upstanding edges of the upper materials. Lasts and shoes vary in shape and width, and a gripper mechanism so constructed as to enable the 100 grippers accurately to be positioned relatively to the lateral periphery of the shoe independently of the eye of the operator is, therefore, very desirable. Another feature of the invention consists in a gripper having 105 novel means to position it relatively to the

work, the construction shown comprising jaws relatively movable to grip upper materials between them, one of said jaws having associated therewith a non-gripping member for engaging the shoe and positioning the gripper in stock-seizing relation to the shoe. This member acts as a feeler and is shown as an offset lug depending from the outer jaw and supporting a contact roller, which is adapted for positioning engagement with the outer side face of the shoe below the plane of the work that is to be gripped. For lasting the toe end of a shoe, for example, two of these gripper mechanisms will be employed at opposite sides of the toe.

In tensioning and stretching the upper materials, grippers may exert excessive strain on said materials, causing them to tear, unless provision is made for relative yield. In addition to the previously mentioned features, the gripper mechanism herein shown is constructed and arranged yieldingly to grip the upper materials between the gripping jaws so that the upper materials may be released if the grippers impose such strain upon the upper materials as to approach the tearing point. As shown, a coiled spring is interposed in the closing means for a pair of gripper jaws, and means are provided for adjusting the tension of said spring so that the gripping tension of the jaws may be varied with different materials to be operated upon.

These, and other features of the invention will be more fully apparent from the detailed specification which follows, when read in connection with the accompanying illustrative drawings, and will be pointed out in the claims.

In the drawings,

Figure 1 is a view in side elevation, partly in section, illustrating a preferable embodiment of the present invention incorporated in the lasting machine of my said application Serial No. 635,183, and

Fig. 2 is a vertical sectional view showing opposite side grippers with their operating mechanism in operative relation to a last and shoe which have been operatively positioned in said machine.

In the machine of said application, two gripper mechanisms are positioned at each side of the longitudinal median line of the toe end of a supported last, the two gripper mechanisms at one side being shown in Fig. 1. The illustrated lasting mechanism includes a wiper head 31 mounted for longitudinal reciprocating movement through a connected power actuated rod 22 and recessed to receive carrier plates 32 provided with recessed edges within which are mounted pivoted wiper plates 33. These wiper plates are swung toward and from each other by a power reciprocated rod 50 piv-

otally connected to the middle portion of an equalizing cross-bar 43 having adjustable and yielding connections with ears 39 depending from the carrier plates 32.

The gripper mechanisms coöperate with this wiper mechanism in the lasting operation and are supported from pivoted carrier bars 148 which are swung toward the opposite sides of a last and shoe supported between them by a cam actuated bell crank lever 161, a bar 160 and links 159 to position the grippers in operative relation to the shoe upper, the bars 148 becoming automatically latched to intergeared pivoted members 172 turned by power operated connections to swing the carrier bars 148 outwardly from the shoe with them in timed relation to the closing of the wiper plates 33 over the bottom of the shoe. Prior to the swinging of the bars 148 outwardly, the open jaws of the gripper mechanisms are closed by jaw closing bars 153 pivoted to the laterally extended end of a lever 166 which is operated by power in timed relation to the wiper and gripper outswing mechanisms.

The gripper mechanisms illustrated in connection with the described lasting mechanism each comprises an outer jaw 146, herein frequently termed a "fixed" jaw since it has no closing movement, this jaw having a vertically extending shank portion 147 secured at its upper end in an opening in the carrier bar 148 previously referred to, and a relatively movable inner jaw 149 having its upper end pivotally attached to a collar 150 free to slide longitudinally on the shank portion 147 of the fixed gripper jaw. The fixed and movable jaws 146, 149 have laterally extended gripping faces, preferably serrated as shown. The fixed jaw is intended to be positioned at the outer side of the shoe upper in substantial alinement with the side face of the shoe and last. The fixed jaws of the grippers have lugs laterally offset and depending from the gripping faces of said jaws in which are journaled "feeler" wheels 157 arranged to engage the side of a shoe supported by and clamped between a toe support 59, 60 and a suitable clamping hold-down 72, for instance, and to position the opening between the open jaws of the gripper in line with the upstanding edges of the upper materials. In the drawings, since each carrier bar 148 supports two gripper mechanisms for swinging movement toward the side of the shoe and last, only one of said gripper mechanisms at each side need be and is shown as provided with a "feeler" or positioning wheel 157.

The movable jaw 149 in its opened position is raised a substantial distance above the sole of a supported shoe (see Fig. 2) and is swung inwardly to provide a relatively wide opening between the jaws to em-

brace all of the upper materials. It is moved to and supported in this position, and in closing is moved bodily downwardly and simultaneously swung outwardly, gathering in all of the upper materials and bringing its gripping face close to the plane of the sole substantially at the end of its closing movement. These movements are effected through an operating lever 151 pivotally mounted at a point intermediate of its ends on the fixed jaw at a point on said jaw between its upper and lower ends, and having one arm, as shown, the shorter arm, pivotally connected to the movable jaw at a point 15 above its lower gripping end, the lever thus serving as a link connection between the jaws. The other arm, as shown, the longer arm, of this operating lever, has a pin and slot connection with the lower end of a vertically movable rod 152, the upper end of the rod extending through an opening in a jaw closing bar 153 with a coiled spring 155 sleeved on the upper end of the rod between the upper face of bar 153 and a tension adjusting nut 154 threaded on the end of said rod. A collar 156 fixed on the rod engages the under face of bar 153 and limits the upward movement of the rod relatively to the bar, determining the area of the upper-receiving opening between the jaws.

The spring 155 normally acts to elevate the rod 152 and to hold the collar 156 against the bar 153. It also forms a yielding element in the jaw closing means so that when the bar 153 is lifted, the jaws 149, 146 will yieldingly grip the upper materials between them and will yield as the tension on the upper approaches a degree predetermined by the adjustment of the spring-tensioning 40 nut 154.

By attaching the movable jaw to the sliding collar 150 and connecting the jaw closing lever to the movable jaw below said collar, the movable jaw, through the action 45 of the lever 151 is carried bodily upward and is coincidently swung inwardly away from the fixed jaw providing a relatively wide area of opening between the jaws to receive the upper materials. When the lever 151 is reversely moved by the jaw closing bar 153, the movable jaw 149 is moved bodily downward with the collar 150 and at the same time swings outwardly 50 toward the fixed jaw, gathering in the upperstanding edges of the upper materials and gripping them between the serrated gripping faces of the fixed and movable jaws. By reason of the combined sliding and swinging movement of the movable jaw, 55 only a comparatively short swinging movement of this jaw and of the lever 151 is required to open and close the gripper mechanism. Additionally, the lower gripping face of the movable jaw, in its closing 60 movement, travels in a curved path which

causes it to gather in all of the upper materials and to grip them close to the bottom face of the sole, and to do this without interference with the bottom of the sole, or, if the movable jaw is positioned on the outer side of the shoe, the edge of the last or sole.

It is contemplated that the gripping face at the lower end of the movable jaw will arrive at its lowest point substantially at 75 the end of its closing movement, as suggested by the dotted line in Fig. 2 indicating the path of closing movement. The movement of this jaw toward and from the fixed jaw has two components of movement, one 80 longitudinally of the fixed jaw substantially parallel with its shank portion, and the other a laterally swinging component about a pivot point progressively approaching or receding from the gripping face of the fixed 85 jaw. This movement enables the grippers to secure the above mentioned advantages when working with shoes having soles with upstanding sewing ribs since the swing of the movable jaw may be and is figured to 90 cause its edge to clear this rib in closing.

Having thus described my invention, what I claim as new and desire to secure by Letters Patent of the United States is:—

1. In a mechanism of the character described, a gripper comprising a fixed jaw, a coöperating jaw pivotally connected to said fixed jaw to swing toward and from the fixed jaw and guided on said fixed jaw for bodily straight line movement of its pivot 100 coincidently with said swinging movement, and means for swinging and simultaneously moving said coöperating jaw in a straight line lengthwise of the fixed jaw.

2. In a mechanism of the character described, a gripper having a fixed jaw and a pivoted, bodily movable jaw, a support for said jaws, a lever connected to the pivoted jaw for closing and opening the jaws and for coincidently effecting bodily movement 105 of the pivoted jaw, an operating member movable relatively to said support, and means yieldingly connecting said lever and said operating member.

3. In a mechanism of the character described, a gripper comprising a fixed jaw and a movable jaw pivotally connected to the fixed jaw for swinging movement toward and from the fixed jaw and mounted for coincident straight line bodily movement of its pivot, and a lever pivotally attached at one end to the movable jaw and intermediate its ends pivotally attached to the fixed jaw.

4. A gripper mechanism comprising a 125 fixed jaw, a relatively movable jaw supported for swinging movement toward and from the fixed jaw and for bodily sliding movement lengthwise of said fixed jaw, and an actuating member pivoted to said fixed 130

- jaw and connected to said movable jaw to effect longitudinal sliding and coincident swinging movement of said movable jaw relatively to the fixed jaw.
- 5 5. A gripper mechanism comprising a fixed jaw, a pivoted relatively movable jaw connected to said fixed jaw for relative longitudinal sliding movement, and an actuating lever fulcrumed on said fixed jaw and having one end connected to said movable jaw to effect longitudinal sliding and coincident lateral swinging movement of said jaw relatively to the fixed jaw.
- 10 6. A gripper mechanism comprising a fixed jaw having a supporting shank portion, a collar mounted on said shank portion for longitudinal sliding movement, a movable jaw pivotally connected to said collar and bodily movable with said collar, and a lever pivoted to said shank portion and having one end connected to said pivoted jaw and arranged, when actuated, to effect longitudinal sliding and coincident lateral swinging movement of said pivoted jaw.
- 15 25 7. A gripper mechanism comprising a fixed jaw having a supporting shank portion, a collar freely slideable longitudinally on said shank portion, a movable jaw having one end pivoted to said collar and bodily movable with said collar longitudinally of the fixed jaw, a lever pivoted on said fixed jaw between its gripping end and said collar and having one end pivotally connected with said movable jaw at a point between its ends, and means for operating said lever bodily to slide said movable jaw longitudinally of the fixed jaw and coincidently to swing said movable jaw toward and from said fixed jaw.
- 20 40 8. A gripper mechanism comprising a fixed jaw, a movable jaw supported for swinging movement toward and from the fixed jaw and for bodily sliding movement lengthwise of said fixed jaw, an actuating member fulcrumed on said fixed jaw and connected to said movable jaw to effect longitudinal sliding and coincident lateral swinging movement of said jaw relatively to the fixed jaw, and means arranged yieldingly to move said movable jaw into stock gripping relation to the fixed jaw.
- 25 55 9. A gripper mechanism comprising a fixed jaw having a supporting shank portion, a pivoted movable jaw having a shank portion connected to the shank portion of the fixed jaw for longitudinal sliding movement relatively thereto, a lever fulcrumed on the shank portion of the fixed jaw and connected to said movable jaw to effect longitudinal sliding and coincident lateral swinging movement of said jaw relatively to the fixed jaw, means acting through said lever normally to hold said jaws longitudinally and laterally separated, and additional
- 30 35 40 45 50 55 60 65 70 75 80 85 90 95 100 105 110 115 120 125 130
- spring means arranged to act through said lever yieldingly to close said jaws together.
10. A gripper mechanism comprising a fixed jaw, a movable jaw, means for supporting said movable jaw for coincident longitudinal sliding and lateral swinging movement from a position laterally and vertically removed from the gripping portion of said fixed jaw, said means being constructed and arranged to bring the gripping portion of the movable jaw into the plane of and in coöperative gripping relation to the gripping portion of the fixed jaw approximately at the end of said sliding and swinging movement, and an actuating lever fulcrumed on the fixed jaw and connected to said movable jaw to effect said coincident sliding and swinging movement.
11. A gripper mechanism comprising a fixed jaw, a pivoted movable jaw, means for supporting said movable jaw for bodily sliding movement longitudinally of the fixed jaw, and an actuating lever fulcrumed on the fixed jaw and connected to said movable jaw to effect in one direction of actuation longitudinal sliding and coincident lateral swinging movement of said movable jaw to position said jaw in a location vertically and laterally removed from the gripping portion of said fixed jaw and in the reverse direction of actuation to effect coincident sliding and swinging movement of the movable jaw in a path to bring its gripping portion into the plane of and in coöperative gripping relation with the gripping portion of the fixed jaw approximately at the end of said coincident sliding and swinging movement.
12. A gripper mechanism comprising co-operating stock seizing jaws, one of said jaws having associated therewith a non-gripping member for engaging the shoe and laterally positioning the gripper in stock seizing relation to the shoe preliminarily to the seizing of the shoe stock by the gripper jaws.
13. A gripper mechanism comprising relatively movable stock gripping jaws, one of said jaws having a non-gripping member associated therewith and arranged to move with said jaw to engage a shoe at a point removed from the gripping point to position the gripper in operative stock gripping relation to the upper materials preliminarily to the seizing of the shoe stock by the gripper jaws.
14. A gripper mechanism comprising relatively movable stock seizing jaws and a non-gripping extension below one jaw adapted for gripper-positioning engagement with the side of a shoe below the portion of the upper materials to be gripped preliminarily to the seizing of the shoe stock by the gripper jaws.
15. Gripper mechanism for use in last-

- ing the toe ends of shoes comprising two grippers adapted to engage an upper at opposite sides of a shoe toe and a non-gripping extension below each gripper for engagement with the opposite sides of the toe portion of the shoe relatively to position the shoe and grippers for the two grippers properly to seize the upstanding shoe upper materials.
- 10 16. A gripper mechanism comprising a fixed jaw arranged to engage the outer side of a shoe upper, a relatively movable co-operating jaw at the inner side of the upper arranged for movement to grip shoe upper materials between it and the fixed jaw, and a non-gripping extension from the fixed jaw arranged for gripper-positioning engagement with the outer side of the shoe upper at a point removed from the gripping point of said jaw in the direction of the top of the last preliminarily to the seizing of the shoe stock by the gripper jaws.
- 15 17. Gripper mechanism for use in lasting the toe ends of shoes comprising two grippers adapted for bodily movement toward opposite sides of the toe end of a last and shoe upper and constructed and arranged to engage the upper materials at said opposite sides, each gripper comprising a fixed jaw at the outer side of the shoe, a relatively movable co-operating jaw at the inner side of the upper, and a non-gripping extension from the fixed jaw arranged for gripper-positioning engagement with the outer side of the shoe upper at a point removed from the gripping point of said jaw in the direction of the top of the last.
- 20 18. Gripper mechanism for lasting shoes comprising two grippers adapted to seize the margin of the shoe stock at opposite sides of the shoe, each gripper comprising relatively movable stock-seizing jaws and having associated therewith a non-gripping member, said members being arranged to engage opposite sides of the shoe to position said grippers in stock seizing relation to the sides of the shoe preliminary to the seizing of the shoe stock by the gripper jaws.
- 25 19. An upper pulling gripper comprising a pair of co-operating gripping jaws elongated substantially in the direction of their pull upon the upper, a link connecting said jaws at points between their opposite ends to cause relative swinging movement of the jaws in closing, and means connecting the outer end portions of the jaws for relative rectilinear movement throughout the entire relative closing movement of the jaws.
- 30 20. A gripper comprising a pair of jaws one of which is mounted to swing laterally toward the other in closing, and means connected to the outer end portion of said swinging jaw to guide the outer end of said jaw in a straight path throughout the entire closing movement of the jaw.
- 35 21. An upper pulling gripper comprising a pair of co-operating gripping jaws, a link connecting said jaws at points between their opposite ends to cause one of the jaws to swing laterally toward the other in closing, and a controlling member pivoted on the outer end portion of said swinging jaw and slidably mounted for rectilinear movement in a direction substantially parallel to the direction of the pull of the gripper throughout the entire closing movement of said jaw.
- 40 22. A gripper comprising a pair of jaws one of which is arranged to engage an upper on its outer side and is held substantially stationary during the closing movement of the other jaw, and means for controlling the closing movement of said other jaw to cause it to swing laterally over the shoe bottom toward the first jaw with a bodily movement from a starting position comparatively remote from the plane of the sole of the shoe and in a direction transverse to said plane throughout its entire lateral swinging movement.
- 45 23. In gripper mechanism, the combination with relatively movable gripper jaws, of an extension on one of said jaws for engaging the lateral periphery of a shoe to position the jaws relatively to the shoe before they close upon the upper material.
- 50 24. In gripper mechanism, the combination with relatively movable gripper jaws, of means on one of said jaws for determining the correct relation of the gripper to a shoe, said means being arranged to engage the lateral periphery of the shoe adjacent to the gripping face of said jaw in a location farther from the edge of the upper than said face.
- 55 25. In mechanism of the class described, the combination with a gripper mounted for positioning movement in a direction transverse to the lateral periphery of a shoe, of means carried by said gripper for engaging the lateral periphery of the shoe to limit said positioning movement.
- In testimony whereof I have signed my name to this specification.

CHARLES F. PYM.
